F. W. REDSHAW,
GRINDER MECHANISM,
APPLICATION FILED JAN. 11, 1917.

1,228,135.

Patented May 29, 1917.

INVENTOR.
Frederick W. Redshaw,
Edward A. Lawrence,
his Attorney.

UNITED STATES PATENT OFFICE.

FREDERICK W. REDSHAW, OF SCOTTDALE BOROUGH, PENNSYLVANIA.

GRINDER MECHANISM.

1,228,135.

Specification of Letters Patent. Patented May 29, 1917.

Application filed January 11, 1917. Serial No. 141,736.

To all whom it may concern:

Be it known that I, FREDERICK W. REDSHAW, a citizen of the United States, and residing in Scottdale Borough, in the county 5 of Westmoreland and State of Pennsylvania, have invented or discovered new and useful Improvements in Grinder Mechanism, of which the following is a specification.

10 My invention consists in a new and improved portable grinder mechanism for jointer and planer knives.

The object which I have in view is the provision of a portable sharpening attachment which may be quickly mounted on a jointer or planer, and as quickly dismounted, and which will accurately grind and balance the knives without requiring their removal from the head.

20 In machinery of this character, it is necessary that the knives be accurately aligned and balanced, and, if the knives be removed from the head for sharpening, the proper resetting of the knives is a tedious operation and one beyond the skill of the ordinary mill mechanic. It is desirable, therefore, to grind the knives without removing them from the head and also without removing the head from the machine. In the

30 use of a portable grinder for this purpose, the same must be capable of positive positioning in relation to the knives, so that no variation or inaccuracy can possibly occur, and the mounting of the grinding member 35 must be such that it will run true in all positions, so that the sharpened knife will be properly balanced.

I accomplish the object in view by providing a relatively light weight grinder 40 mechanism which is conveniently portable and which, when mounted on the jointer or planer positively assumes and maintains the exact position required for the accurate sharpening and balancing of the knives.

45 The frame of the mechanism is rigid or integral to prevent loss of alinement or movement of its parts, and it is provided with fixed means which engage recesses in the jointer or planer and positively fix the position of the frame in relation to the knives to be sharpened. A driven shaft is mounted in said frame and an emery wheel is mounted on said shaft to rotate therewith,

and to be slid along the length thereof by means of a yoke which is slidably mounted on said driven shaft and on a guide shaft parallel with said driven shaft. 55

Novel features of construction and arrangement of parts will appear from the following description. 60

In the accompanying drawings, Figure 1 is a rear elevation showing my improved grinder mounted on the back bed of a jointer, the bed and one of the knives being shown in dotted lines; Fig. 2 is a vertical section along the line II—II in Fig. 1, the front and rear beds and the rotary head with one of its knives being shown in dotted lines, and Fig. 3 is a broken vertical section through the axis of the emery wheel 70 to show its mounting on the driven shaft. 65

The following is a detailed description of the drawings.

A represents the rear bed of the jointer; B the front bed of the same; C the rotary 75 head, and D one of the knives mounted in said head.

In machines of this kind, adjusting mechanism is provided whereby the beds may be kept accurately positioned and leveled in relation to the head and its knives. I do not show such mechanism as it is not in itself a part of the present invention. 80

Referring now to my grinder mechanism, E is a cast metal frame, preferably 85 integral but which, if so desired, may be built up of elements which are rigidly connected together so that no movement or variation may occur between parts of the frame. I recommend a solid, integral 90 frame. 1 is the base of the frame comprising a substantial plate or member which, when the grinder mechanism is mounted on the jointer or planer, rests flat upon and is positioned transversely of the rear bed A 95 in parallelism with the head D. The lower face of said base 1 is provided with a plurality of depending dowels or projections 2 which engage accurately fitting recesses or holes 3 cut into the bed A. 4 are set screws 100 extending through the base 1 and engaging threaded holes 5 in the bed A. 105

It is perfectly evident that by the combined use of the dowels and set screws the frame may be both firmly clamped and accurately positioned in place, and when-

ever the grinder mechanism is mounted on the jointer or planer, it will always assume and maintain the same exact position.

6 and 7 represent a pair of brackets, integral with and extending forwardly from the base 1 so as to occupy vertical planes beyond the ends of the knife D when the grinder mechanism is in position for use. The outer ends of said brackets are provided with alined bearings 8 and 9. 10 is a third bracket spaced outside of bracket 7 and parallel therewith. 11 is a bearing in bracket 10 alined with bearings 8 and 9. 12 represents bushings inserted in bearings 15, 6, 7 and 10.

13 is a rotary shaft journaled in bushings 12 and held against longitudinal movement by set collars 14 fixed on the ends of the shaft. 15 is a pulley or band wheel rigidly 20 fixed on the shaft 13 between the brackets 7 and 10, whereby rotation may be imparted to the shaft 13. The pulley may be operated by a belt from the counter shaft of the jointer.

25 F is an emery wheel or other rotary grinder mounted on said shaft 13 so that it rotates with said shaft and may be slid along the same at the will of the operator. Thus, I have shown the emery wheel provided axially with a cylindrical lead core 16 within which is a paper lining 17 and a metal bushing 18 threaded at either end for the application of lock nuts 19. 20 is a feather key fixed to and extending inwardly from the bushing 18 to engage a slot 21 cut in the shaft 13 and extending between the brackets 6 and 7. Thus the grinder rotates with the shaft 13 and may be slid along the same between the brackets 6 and 7.

40 G is a bifurcated carriage provided with parallel arms 22 which form a yoke which encompasses the axis of the emery wheel F. Said arms are provided with snugly fitting bearings 23 through which the shaft 13 extends, thus slidably mounting the carriage on the shaft 13.

24 is a fixed shaft, parallel with shaft 13 and having its ends secured in the bases of the brackets 6 and 7. Said shaft 24 extends 50 through a snugly fitting transverse hole 25 in the carriage G. 26 is a handle or hand grasp fixed to said carriage.

It is evident that while the emery wheel F is revolving, it may be slid along the shaft 13 to reach and grind every portion of the knife edge, by moving the carriage G, the shafts 13 and 24 acting as guides to prevent lateral swaying movement of the wheel out of a true vertical plane.

60 It is evident from the foregoing that my grinder mechanism is relatively light in weight, of very economical and durable structure, and may be readily mounted on or dismounted from the jointer or planer 65 without requiring delicate adjustment or

positioning. It may be set down into place with positive assurance that the knives will be ground true and perfectly balanced. The frame is perfectly rigid and contains no parts capable of adjustment or change. The emery wheel, being controlled by a carrier which is transfixed by parallel shafts, slides readily along the driven shaft without lateral sway or movement out of a true vertical plane. This is very important as such swaying or inclination would result in an uneven cutting edge for the knives.

What I desire to claim is:—

1. A grinding mechanism for sharpening the knives of jointers and planers without removing the latter from the machine, and comprising a flat base plate adapted to be laid transversely on the bed of the machine, adjacent and parallel to the rotary head thereof, and provided with depending positioning dowels, the bed of the machine being provided with holes to receive said dowels and accurately position the base plate of the grinder, means independent of said dowels and holes for holding said base plate rigidly on said bed, a pair of brackets permanently rigid with said base plate and so located as to extend one at either side of the bed plate of the machine, a third similar bracket spaced outwardly from one of said first named brackets, a rotary shaft journaled parallel with said base plate in all three of said brackets, a power pulley rigidly mounted on said shaft between said third bracket and the adjacent one of said first mentioned brackets, a grinding wheel slidably mounted on said shaft but rotating therewith, a bifurcated carriage embracing said wheel and slidably mounted on said shaft, a guide shaft parallel with said first mentioned shaft and extending between the first mentioned pair of brackets, said carriage being provided with a horizontal hole through which said guide shaft extends, and a hand grasp for said carriage, substantially as and for the purposes set forth.

2. A grinding mechanism for grinding the knives of jointers and planers without removing the latter from the machine, and comprising a metal frame consisting of a flat base plate adapted to rest upon and transversely of the bed of the machine, said base plate being provided with depending members which seat in accurately fitting recesses provided in the bed of the machine to insure exact positioning of the grinding mechanism, and three parallel brackets cast integrally with said base plate, one bracket being located at either side of the bed plate of the machine, and a third bracket outside of and adjacent to one of said first mentioned brackets, a rotary driving shaft journaled in all three brackets, a driving pulley rigid with said shaft between said third bracket and the adjacent one of said first

mentioned brackets, a grinding wheel sliding on and rotated by said shaft, a guide shaft mounted on said frame parallel with said first mentioned shaft, a carriage sliding 5 on both of said shafts and controlling the sliding motion of said wheel, and clamping means independent of said members and

said recesses, for holding said grinding mechanism rigidly in place on said machine, substantially as and for the purposes set forth.

Signed at Scottdale, Penna., this 5th day of Jan., 1917.

FREDERICK W. REDSHAW.
